Inventor,
John Carlson.

UNITED STATES PATENT OFFICE.

JOHN CARLSON, OF SMETHPORT, PENNSYLVANIA.

CAR-COUPING.

SPECIFICATION forming part of Letters Patent No. 388,948, dated September 4, 1888.

Application filed May 19, 1888. Serial No. 274,388. (No model.)

To all whom it may concern:

Be it known that I, JOHN CARLSON, a citizen of the United States, residing at Smethport, in the county of McKean and State of Pennsylvania, have invented a new and useful Improvement in Car-Couplings, of which the following is a specification.

The invention relates to improvements in car-couplers; and it consists in the construction and novel combination of parts herein-after described, and pointed out in the claims.

Figure 1 of the drawings is a perspective view of the end of a car having a coupler embodying the invention attached. Fig. 2 is a central vertical longitudinal section of the said coupler.

Referring to the drawings by letter, A designates a draw-head attached to the draw-bar a, secured to the end of the car. 20 a' a² are respectively the upper and lower coupling-pin holes of the draw-head, and B is the longitudinal recess therein to receive the link b.

C is a metal frame secured to the top of the draw-head, and composed of the semicircular vertical end straps, c c, and the longitudinal connecting-bars c', the top one of which is provided with the openings c² vertically above the coupling-pin openings, and through which 30 the said pin passes.

D D are vertical guide-bars rising from the top of the respective end straps, c, to which their upper ends are secured.

E is a coupling-pin, having the circumferential shoulder e near its top and the circumferential shoulder e' near its bottom, and E' is a lifting-plate, having the pin-opening e², upon which the shoulder e rests, and the directing end openings, e³, through which the 40 guide-bars D pass.

F is a transverse shaft, having bearings f secured to the upper surface of the draw-head, and provided with the central frontwardly-standing crank, f', that rests under the lifting-plate E'.

f² is an outwardly-standing crank on said shaft outside of the draw-head, and f³ f³ are crank-handles on the ends of said shaft outside of the ends of the cars, to which the coupler is attached.

It is evident that the brakeman can raise

the lifting-plate E', and thereby the coupling-pin E, by means of either handle at either side of the train.

G is a curved lever pivoted about centrally 55 to a staple or loop standing outward from a vertical bar, g, secured to the outer surface of the draw-bar. The said lever has a suitable handle, g', on its upper arm, and has the end of its lower arm connected by the link-rod g² to 60 the crank f². The handle g' extends upward sufficiently far to permit the brakeman, when on top of the train, to use it, and thereby lift the plate E' and the coupling pin E to uncouple the cars.

H is a short threaded rod passing through the block h, which has an outer face of metal. The said rod has a head, J, provided with a shoulder, j', that engages over the link when the latter is engaged by the pin and holds it 70 horizontal.

j is a plate secured against the inner surface of the block h, with its upper part bent forward over the top of the block, and having its outstanding edge made concave to catch on the shoulder e' and hold the pin up when the latter is raised. The bolt H is held to the block 75 h by a nut which engages its end, as shown.

I is a spring, which has one end secured to and bearing against the inner side of the block 80 h and the other end secured to and bearing against the floor h² of the draw-head recess h'.

When the pin has been raised by the lifting-plate and the plate allowed to fall, the pin is held up by the concave edge of the plate j 85 catching on the shoulder e'. Then, when the cars couple, the entering link drives back the block H, the said plate is disengaged from the shoulder on the pin, and the latter falls in the link.

Having thus described my invention, I 90 claim—

1. In a car coupler, the combination of the draw-head, the coupling-pin having a circumferential shoulder near its top, the lifting-plate, 95 and the transverse crank-shaft having bearings on the draw-head, substantially as specified.

2. In a car-coupler, the combination of the draw-head, the coupling-pin having a circumferential shoulder near its top, the lifting-plate, 100 the frame C, having the opening c² for the pin, and the guide-bars D for the lifting-plate, and

the transverse crank-shaft having bearings on the draw-head and acting on the lifting-plate, substantially as specified.

3. In a car-coupler, the combination, with 5 the draw-head, the coupling pin having a circumferential shoulder near its top, and the lifting-plate, of the shaft F, journaled in bearings on the draw-head and provided with the cranks $f' f^2$ and crank-handles f^3 , the curved 10 lever G, pivoted to the vertical bar g, and the link-rod g' , connecting the lower end of said lever with the crank f^2 of the shaft F, substantially as specified.

4. In a car-coupler, the combination, with 15 the draw-head, the pin having the circumferential shoulders $e e'$, the lifting-plate, and the crank-shaft journaled on the draw-head, of the

threaded rod H, the spring I, the block h, and the plate j, having its outstanding end concave to engage the shoulder e' , substantially as 20 specified.

5. In a car-coupler, the combination, with the pin and link, of the spring I, the block h, and the threaded rod or bolt H, having the head J, provided with the shoulder j' to engage the upper surface of the end of the link, 25 substantially as specified.

In testimony that I claim the foregoing as my own I have hereto affixed my signature in presence of two witnesses.

JOHN CARLSON.
